(57) CLAIM

The ornamental design for a root defender, as shown and described.

DESCRIPTION

FIG. 1 is a front elevation view of a root defender. FIG. 2 is a side elevation view of the root defender of FIG. 1. FIG. 3 is a top plan view of the root defender of FIG. 1. FIG. 4 is a bottom plan view of the root defender of FIG. 1. FIG. 5 is an isometric view of the root defender of FIG. 1; and, FIG. 6 shows a portion of the mesh material which forms the sidewalls of the root defender of FIG. 1 at an enlarged scale. The broken lines showing a plant are included to show environmental subject matter only and form no part of the claimed design.
